2 SHEETS—SHEET 2.

A technical line drawing of a window frame. The frame is rectangular with a cross-brace at the top. The left side has a vertical bar with the number '121' above it. The top horizontal bar has the number '131' to its left. The right side has a vertical bar with the number '181' above it. The bottom horizontal bar has a vertical line with the number '181' to its left. The entire frame is enclosed in a thick border.

UNITED STATES PATENT OFFICE.

JAMES T. VULGAMOTT, OF WOOLSTOCK, IOWA.

CONVEYER.

1,204,620.

Specification of Letters Patent.

Patented Nov. 14, 1916.

Application filed March 10, 1915. Serial No. 13,522.

To all whom it may concern:

Be it known that I, JAMES T. VULGAMOTT, a citizen of the United States, residing at Woolstock, in the county of Wright and 5 State of Iowa, have invented certain new and useful Improvements in Conveyers, of which the following is a specification.

This invention relates to conveyers, the primary object being, to devise a mechanism 10 for conveying seed, etc., from a source of supply to a hopper or other means, which controls the flow of the feed, to facilitate planting.

Another object of the invention is to so 15 construct the conveyer, that the latter may be conveniently associated with standard types of wagons or other vehicles, and which will be operated by the traction of the wagon or vehicle.

20 Still another object of the invention is to equip the conveyer with suitable mechanism by which it is thrown into or out of operative connection, with or from, respectively, the traction wheels of the vehicle; the mechanism likewise controlling feeding of the 25 material from the source of supply.

Other objects as well as the nature, characteristic features and scope of my invention will be more readily understood from the 30 following description taken in connection with the accompanying drawings and pointed out in the claims forming a part of this specification.

Referring to the drawings: Figure 1 is a 35 longitudinal sectional view of the device constructed in accordance with my invention, illustrating the application of the same in a wagon, the latter being likewise shown in longitudinal section, Fig. 2 is a top plan 40 view of the same, portions thereof being broken away to disclose details, Fig. 3 is a cross sectional view taken on the line 3—3 of Fig. 2, and looking in the direction of the arrows, Fig. 4 is a transverse sectional view 45 of the front of the wagon box illustrating the manner in which the conveyer supporting frame is mounted therein, Fig. 5 is a detail enlarged fragmentary side elevational view of the means for regulating the feeding 50 of materials to the conveyer, and for throwing the latter into or out of engagement with the traction wheels, and Fig. 6 is a detail enlarged fragmentary section and fragmentary side elevational view, respec-

tively, of one of the conveyer supporting 55 members, showing the manner in which the gear-wheel is associated therewith.

In the drawings wherein is illustrated the preferred embodiment of this invention, a wagon 1 is provided, which in the present 60 instance is of the usual configuration, including an oblong box of the usual contour in which is mounted my improved conveyer mechanism generally designated 2.

The conveyer mechanism 2 embodies an 65 endless run 3 preferably made of canvas and having mounted thereon at equidistant points, ribs 4 in order to preclude possibility of displacement of the seed or grain when the latter is being conveyed on the inclined 70 portion of the conveyer, as hereinafter described. Strips 5 are superposed upon the terminals of the ribs 4, and extend longitudinally of the conveyer, so as to serve in the dual capacity of preventing the accidental displacement of the ribs 4, and likewise preventing lateral displacement of the grain from the conveyer. It will be noted that the lower end of the conveyer is arranged in 75 parallelism with the bottom of the wagon 80 body and has its terminals trained about the periphery of a roller 6, the latter being journaled between parallel side members 7. The side members 7 are hinged to the bottom of the wagon box, so as to be 85 folded into engagement with the latter, for occupying a minimum amount of space when not in use. One of the ends, of each of the side members 7, is snugly engaged with the front of the wagon box, 90 while the opposite end of each is appreciably spaced from the end gate and is conjoined, through the instrumentality of links 8, to parallelly arranged supporting bars 9, as 95 illustrated to advantage in Fig. 5. The bars 9 are set at an inclination in the wagon box and have mounted between the outer or free ends thereof a shaft 10 upon which is revolubly mounted a roller 11. One end of the conveyer is arranged in parallelism with 100 the members 9 and has its upper end trained about the roller 11.

Mounted in the wagon box above that portion of the conveyer which extends in parallelism with the bottom of the wagon 105 box, is the perforate bottom 13, the perforations in the present instance extending along the longitudinal axis of the bottom 13,

so as to emit the contents of said receptacle 12 onto the upper run of the conveyer. Inclined sides 14 are associated with the bottom 13, in order to facilitate the seed or other material which is retained in the receptacle 12 to gravitate to the bottom 13.

Slidably mounted subjacent the bottom 13 is a slide 15, the latter being made of wood, metal or any other suitable material and 10 provided with a series of perforations 16, extending along the longitudinal axis thereof, which are adapted to aline with the perforations 14' in the bottom 13 of the receptacle 12. Guides 17 are mounted upon 15 the lower face of the bottom 13 and are adapted to receive the slide 15, so as to prevent accidental displacement of the latter during movement. In order to facilitate movement of the slide 15, an ear 17' is 20 formed on one of the lateral margins of said slide and has its free end in engagement with one end of the link 18 through the medium of which the slide 15 is operated, for alining the openings 16 thereof with the 25 opening 14' of the bottom 13, at the option of the operator.

A frame 17' is mounted in the rear end of the wagon box and in the present instance comprises a base portion which is secured to the bottom of the wagon box, the latter having a plurality of uprights extending therefrom, with the upper terminals of said upright in fixed engagement with the upper horizontal bar of said frame 17'. The 30 vertical uprights are retained from displacement by suitable brace rods, the latter being in engagement with the base of the frame 17', as shown to advantage in Fig. 4.

The free ends of the members 9 are secured in any suitable manner to the frame 17', whereby said members are retained in a desired inclined position in the wagon box, so as to dispose the outlet end of the conveyer at a point directly above the end gate 45 18' of the wagon box.

A gear wheel 19 is slidably mounted in an elongated opening 20 in one of the members 9, said gear wheel having a stub-shaft extending therefrom, upon which is formed, 50 a pair of parallel annular flanges 21, one of said annular flanges lying on one side of the slot 20 and the other one on the other side of the slot. By this formation, it is seen that the gear-wheel 19 may be moved 55 under pressure, at the same time being held from lateral displacement by the annular flanges 21. A shaft 22, which is an extension from the stub-shaft of the gear-wheel 19, hereinbefore referred to, extends outwardly from the gear-wheel 19 on the opposite side from said stub-shaft, and is in 60 slidable connection with a collar 23, the latter being formed on one end of an operating rod 24, the opposite end of the latter being screw-threaded and having a nut 24' ad-

justably mounted thereon, whereby the tension of a coil-spring 25, which is sleeved on the rod 24, is adjusted. One end of the coil-spring 25 engages the nut 24' and the opposite end engages an ear 26, which extends laterally from an operating lever 27.

The operating lever 27 is pivoted adjacent its lower end upon a rack segment 28, as shown to advantage in Fig. 5, said lever having a portion extended from its inner face to engage the teeth of said rack segment for holding the lever in a predetermined adjusted position. The lower end of the lever 27 has a pintle 29 extending therefrom, which is mounted for movement in an arcuate slot 30, the latter being formed in one of the members 9, adjacent its jointure with a member 7, heretofore described. By mounting the pintle 29 in the slot 30, it is seen that movement of the lever 27 is limited to a predetermined arc, thereby precluding possibility of rendering the lever inoperative by moving the same beyond a certain phase of movement. The lever 27 is in connection with one end of the link 18, whereby when pressure is exerted upon said lever, it will simultaneously operate the slide 15 and exert pressure upon the rod 24, so as to throw the gear-wheel 19, with which said rod is associated, into or out of engagement with a gear-wheel 31. The gear-wheel 31 is mounted upon one end of the shaft 10, so that by imparting movement to said gear-wheel, motion will be transmitted to the shaft 10 for rotating the roller 11, thereby imparting movement to the conveyer 3.

A hopper 33 is mounted upon the end gate 18' subjacent the dispensing end of the conveyer, and is preferably of a conical configuration, tapering from its upper margin to its lower end, in order to dispense its contents in a restricted flow for facilitating planting. The volume of flow from the container 33 is regulated by the usual mechanism, so that only a predetermined quantity 105 of material will be permitted to be deposited in the earth at each specific point. A sprocket-chain 34 is trained about a gear-wheel on the mechanism, in order to operate the latter, said chain being likewise 110 trained about a gear-wheel upon the shaft 22, for rotating the latter upon the operation of the sprocket-chain. A main drive-chain 35 is associated with one of the traction wheels of the vehicle and is trained 115 about a sprocket-wheel, in proximity to the sprocket-wheel about which the chain 34 is trained, so as to transmit motion by the traction of the vehicle through the drive chain 35, to the sprocket chain 34, subsequently imparting movement to the shaft 10 for actuating the conveyer about the periphery of the rollers 6 and 11.

In order to retain the upper and lower runs of the conveyer in a predetermined 120

position at the jointure of the inclined and horizontal portions of the latter, suitable rollers 36 are provided, the upper of which likewise tends to press the materials into the upper run of the conveyer for reducing possibility of displacement of the materials to a minimum. In operation therefore it is seen that the feed or other material which is to be dispensed through the hopper 33, 5 is first placed in the receptacle 12, and the lever 27 set at the proper position, so as to aline the openings 14' in the bottom of the receptacle, and the openings 16 in the slide 15, at the same time engaging the gears 19 10 and 31 in mesh. By the movement of the vehicle, therefore, motion will be imparted to the conveyer in a manner heretofore described, so as to convey the materials, which gravitate through the openings 14' and 16, 15 into the conveyer 33, and from thence to the earth. It is, of course, appreciated that as soon as the vehicle stops, the movement of the conveyer is also curtailed, as well as the mechanism, which is run incidental to 20 the operation of the vehicle. It is furthermore to be understood that when so desired, the conveyer may be rendered inoperative, even while the vehicle is in motion, by suitably adjusting the lever 27, this positioning 25 of the latter likewise disalining the openings 14' and 16, so as to close communication therethrough.

It will be understood that the above description and accompanying drawings comprehend only the general and preferred embodiment of my invention and that various minor changes in details of construction, proportion and arrangement of parts may be made within the scope of the appended claims and without sacrificing any 35 of the advantages of my invention.

Having thus fully described my invention what I claim as new and desire to secure by Letters Patent is:

40 1. The combination with a vehicle body, of side members hinged to said body and normally supported in vertical position upon the bottom of said body, rollers supported by said side members, extension members 45 for said side members, a roller carried by said extension members, a conveyer belt engaged around said rollers, a receptacle resting upon said vehicle body and said side members, means carried by said vehicle for 50 retaining said side members in vertical position, means for controlling the discharge of material from said receptacle to said conveyer belt, a hopper supported beneath one end of said conveyer belt, and 55 means for operating said conveyer belt to 60 deliver the material to said hopper.

2. The combination with a vehicle body, of parallel side members hinged upon the bottom of said body, inclined extension members for said side members, means for connecting said extension members with said side members, an endless conveyer mounted between said side members and between said extension members, a hopper mounted upon one end of said vehicle body 65 and beneath the upper end of said conveyer, a receptacle mounted upon said side members and said vehicle body to deliver material to said endless conveyer, a slide for controlling the amount of material delivered to said endless conveyer, means for operating the feed mechanism of said hopper from a wheel of the vehicle, a shaft adapted to be operated upon operation of the feed mechanism of said hopper, a lever 70 mounted upon one of said extension members, and oppositely directed connecting members leading from said lever to said slide and to one end of said endless conveyer to operate said slide and form connections 75 between said endless conveyer and said shaft upon movement of said lever in one direction.

3. The combination with a vehicle body, of parallel side members hinged upon the bottom of said body and adapted at times to be folded downwardly upon the same, a receptacle having a flat bottom and inclined sides, means carried by said inclined sides for engagement with the outer faces 90 of said side members to support the latter in an upright position, the bottom of said receptacle being perforated, a perforated guide member adapted to register with the perforations of said receptacle bottom, 95 guide means for said slide member, extension members for said side members, an endless conveyer mounted between said side members and said extension members, one end of said endless conveyer being inclined, 100 a hopper mounted upon the upper extremities of said inclined end, the feeding mechanism of said hopper being adapted to be operated upon movement of the vehicle body, said endless conveyer being adapted 105 to be operated upon the feeding mechanism of said hopper, and single controlling means for said slide and said endless conveyer.

In testimony whereof I affix my signature in presence of two witnesses.

JAMES T. VULGAMOTT.
